UNITED STATES PATENT OFFICE.

ALBERT C. MOWITZ, OF COLLINGSWOOD, NEW JERSEY, ASSIGNOR OF ONE-HALF TO
HENRY TIEDEMANN, OF CAMDEN, NEW JERSEY.

DISPLAY-CASE.

1,125,870.

Specification of Letters Patent. Patented Jan. 19, 1915.

Application filed May 26, 1914. Serial No. 841,037.

To all whom it may concern:

Be it known that I, ALBERT C. MOWITZ, a citizen of the United States, residing at Collingswood, in the county of Camden and 5 State of New Jersey, have invented certain new and useful Improvements in Display-Cases, of which the following is a specification, reference being had therein to the accompanying drawing.

10 It is an object of this invention to provide in a display-case means whereby, when the case is opened, goods therein will be raised to a higher position than they occupy when the case is closed, and whereby the closing of 15 the case will result in return of the goods to normal or lower position.

The case more particularly is designed to hold and display clothing or the like carried on hangers, and the arrangement is such 20 that, when the top and part of the front of the case, which are connected rigidly together, are opened, a bar extending longitudinally of the case and supporting the goods will be raised, whereby the goods are 25 brought to position of better display and where they are more easily accessible for removal.

When read in connection with the description herein, the details of construction and 30 arrangement of parts contemplated by the invention will be apparent from the accompanying drawings, forming part hereof, wherein an embodiment of the invention is disclosed, for purposes of illustration.

35 While the embodiment disclosed now is considered a preferable one, it is to be understood that it merely is exemplary of the principles of the invention, that it is not the intention to be limited necessarily thereto in 40 interpretation of the claims, and that changes within the limits of the claims can be made without departing from the nature and spirit of the invention.

Like reference-characters refer to corresponding parts in the views of the drawings, of which—

Figure 1 is a front view, showing the case open; Fig. 2 is a transverse sectional view, the parts being in closed position; Fig. 3 is a 50 transverse sectional view, the parts being in open position; Fig. 4 is a fragmentary horizontal sectional view, at the pivotal point of the carrier; and Fig. 5 is a fragmentary

horizontal sectional view, at the pivotal point of the lever.

55

Having more particular reference to the drawings, 6 designates the bottom, 7 the ends, and 8 the back of a display-case. A fixed part 9 of the front of the case closes the lower portion at the front, and at the 60 rear of the top a fixed part 10 of the cover extends for a short distance from the back of the case. The remainder of the front and top of the case is closed by a frame carrying panes of glass or other transparent material 11, and the frame comprises a front portion 12 and a top portion 13 rigidly connected together at an angle corresponding to the end shape of the case, as at right angles in the embodiment shown.

70

Inside of the case at or near each end a base 14 is secured to the bottom, and from this rises a standard 15 extending nearly to the top of the case. Each standard at or near its top has a rearwardly-extending 75 bracket 16, on which is pivotally mounted a carrier 17. The frame comprising the front and top portions 12 and 13 is secured at its ends to the carriers 17, and the parts are so proportioned and located that the frame 80 may be swung on the carriers to position completely to close the case at the front and top or swung from closed position to that at which the top has vertical and the front horizontal disposition and the case opened at 85 which time the front is considerably above the top edges of the ends 6.

Each standard 15 is of hollow formation, and therein is a vertically movable slide 18. A rod or bar 19 is secured to and supported 90 by the slides, and this bar is arranged to have goods in the case hung thereon. Each slide in its lower portion is formed with a rack 20, which extends outwardly of the standard and in mesh with which is a 95 toothed segment 21 on an end of a lever 22 pivoted intermediate its ends on a bracket 23 extending rearwardly from the lower portion of the standard.

A link or rod 24 is connected pivotally to 100 the lever 22 at or near the end opposite to the toothed segment and to the carrier 17 above it; and by this connection, when the frame is swung to open or closed position, the slides, through the instrumentality of 105 the segments and racks, are moved upwardly

or permitted to move downwardly and the bar or rod 19 carrying goods is moved to bring the goods to display or retracted positions. In order to keep the frame in open position and to prevent downward movement of the slides under the influence of the weight of the goods imposed thereon, a counter-weight 25 may be hung on each lever 22 and a counter-weight 26 may be secured to the carriers at places distant from their pivotal points or such a weight may extend along the full length of the hinged top near its rear edge.

Each slide is prevented from lateral displacement from its standard by engagement of its rack in the lower portion with the toothed segment of the lever and by lugs or projections 27 abutting the rear side of slide at the top, the latter formation being shown by Fig. 4.

When it is desired to open the case, a handle 28 at the front of the frame is grasped by the hand and the frame swung upwardly and rearwardly until the top has reached substantially vertical position and the front substantially horizontal position, the movement being stopped at the proper time by contact of the hinged portion of the top with the fixed part 10 of the top and the parts being held in open position by the counter-weights. During the opening movement, the slides and the goods-supporting bar or rod are moved upwardly. The case is closed by a reversal of this operation.

Copies of this patent may be obtained for five cents each, by addressing the "Commissioner of Patents, Washington, D. C."

Having thus described my invention, what I claim as new, and desire to secure by Letters Patent, is—

1. A display-case having a standard near each end, a carrier pivotally mounted on each standard, a closure for the case secured to the carriers, on each standard a vertically-movable slide having a rack, a support for goods carried by the slides, pivotally mounted on each standard a lever having a toothed portion in mesh with said rack, and an operating connection between the carrier and lever on each standard.

2. In a display-case, a fixed hollow standard, a vertically movable slide therein having a rack on its lower portion, a support for goods mounted on the slide, a bracket extending laterally from the lower portion of the standard, a lever pivotally mounted intermediate its ends on said bracket and having at one end a toothed segment in mesh with said rack and a link pivotally connected near its other end, a bracket extending laterally from the upper portion of the standard and having a carrier pivotally mounted thereon, said link being pivotally connected to said carrier, and a closure for the case secured to said carrier.

In testimony whereof I affix my signature in presence of two witnesses.

ALBERT C. MOWITZ.
